DESIGN FOR A DRESS

Marie R. Berger, New York, N. Y.

Application November 8, 1937, Serial No. 72,681

Term of patent 3½ years

To all whom it may concern:

Be it known that I, Marie R. Berger, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed of the super-imposed Shirred units on the skirt section as shown.

I claim:

The ornamental design for a dress, substantially as shown, and described.

MARIE R. BERGER.
